UNITED STATES PATENT OFFICE.

JOHN B. PAXTON AND ELLIS I. O'NEILL, OF PHILADELPHIA, PENNSYLVANIA.

CIRCULAR-KNITTING MACHINE.

SPECIFICATION forming part of Letters Patent No. 595,889, dated December 21, 1897.

Application filed October 15, 1895. Serial No. 565,733. (No model.)

To all whom it may concern:

Be it known that we, JOHN B. PAXTON and ELLIS I. O'NEILL, citizens of the United States, residing in the city and county of Philadelphia and State of Pennsylvania, have invented certain new and useful Improvements 5 in Circular-Knitting Machines, of which the following is a full, clear, and exact description, reference being had to the accompanying 10 drawings, forming a part of this specification.

This invention relates particularly, though not exclusively, to that class of circular-knitting machines technically termed "three-quarter automatic," in which are provisions 15 for automatically effecting the disengagement from and reengagement with the knitting-cams of those needles which are usually manipulated during the formation of the heel and toe parts of a stocking.

20 The present improvements apply more especially to machines in which the needle-controlling mechanism is in the nature of spring-actuated pickers that are periodically projected into the path of the active and inactive 25 needles to effect the requisite disposition of such needles in respect to the knitting-cams. Needle-picking mechanism of this character is set out in our Letters Patent of the United States, No. 521,218, dated June 30 12, 1894, to which reference may be had.

The leading features of the invention herein described comprehend, first, certain improvements in the needle-picking mechanism and in the means for controlling the same; 35 secondly, means whereby the continuous rotary and the reciprocating rotary movements are imparted to the cam-cylinder; thirdly, a novel construction and arrangement of cam for depressing the half-series of inactive 40 needles upon the completion of the heel or toe fastening operation; fourthly, means whereby the tension of the stitches may be varied at predetermined intervals; fifthly, a novel construction of sinker mechanism, and, 45 finally, various features of construction and organization of parts which will be herein-after particularly described and claimed.

In the annexed drawings, Figure 1 is a plan of the machine, the needle-cylinder and part 50 of the driving mechanism being omitted. Fig. 1^a is a sectional detail of a pawl-controlling arm hereinafter referred to. Fig. 2

is a front view of the machine with parts broken away for clearness. Fig. 3 is a view of the left-hand end of the machine at and 55 below the bed-plate. Fig. 4 is a plan of the belt-shipper and adjuncts. Fig. 5 is an elevation of the pawl-and-ratchet mechanism for actuating the pattern-chain which controls the tube-knitting operation. Fig. 6 is a 60 transverse vertical section, as on the line *xx* of Fig. 1. Fig. 7 is an elevation of the driving mechanism. Fig. 8 is a development of the exterior of the cam-cylinder and the needle-controlling mechanism thereon. Fig. 9 65 is a development of a portion of the interior of the cam-cylinder. Fig. 10 is a section through the clutch and fast pulley, as on the line *yy* of Fig. 6. Fig. 11 is a diagram illustrating as in operation the diagonal cam for 70 depressing into action the half-series of idle needles. Fig. 12 illustrates a modification of said cam. Fig. 13 is a detail of the check-cam which coacts with the needle-depressor. Fig. 14 is a plan of the needle-cylinder and 75 sinker mechanism. Fig. 15 is a section enlarged, as on the line *zz* of Fig. 14. Fig. 16 is a development of the sinker-actuating cams.

The bed 1, needle-cylinder 2, rotatable 80 cam-cylinder 3, and knitting-cams 4 are, excepting as hereinafter described, of usual construction. The flanged base of the cam-cylinder is supported upon the bed-plate and is provided with bevel-gear teeth, which coact 85 with the teeth of a bevel-wheel 6 on a horizontal driving-shaft 7, as ordinarily.

Fitted to an inclined slot in the wall of the cam-cylinder, at a point in advance of the knitting-cams, is a reciprocative cam 8, which, 90 preparatory to the knitting of fashioned work, is projected into the needle-cylinder for the purpose of deflecting upward out of action one-half of the circular series of needles. The construction and operation of this cam 95 being fully set out in our previous patent no detailed description thereof is deemed necessary in this case.

Upon the cam-cylinder is supported suitable needle-picking mechanism, which, for 100 the sake of illustration, is represented as of the character described in our said patent—that is to say, there are a pair of lifters 9 and a pair of depressors 10. Each of these mem-

bers comprises a vertical post 11, suitably disposed on the flange of the cam-cylinder, an arm 12, mounted on the post so as to be rotatable and vertically-movable thereon, a cam 13, constructed and arranged to effect the requisite movements of the arm when a needle is engaged by the latter, and a spring 14, arranged to return the arm to a normal or active position in opposition to the cam.

5 In our previous construction, as will be seen by reference to our former patent, the lifters and depressors were moved to their idle position or permitted to return to their active position by properly rotating the individual 15 cam-heads by hand, it being understood, of course, that during the knitting of tubular work—as, for example, the leg or foot of a stocking—the entire picking mechanism is idle, that during the operation of narrowing— 20 in the formation of the heel or toe, for instance—the lifters only are active, and that during the complementary widening operation the depressors only are active. In our 25 present construction, however, the cam-heads are fixed and there is provided a simple and efficient means whereby the lifters may be simultaneously moved into action preparatory to the operation of narrowing and the depressors are moved downward below the 30 path to which the heels of the needles are raised by the lifters during such operation and whereby the lifters are automatically raised out of action and the depressors moved into action preparatory to the succeeding 35 widening operation.

The picker-controlling means comprises a segmental plate 15, fitted to and guided in recessed plates 16, that are secured to suitably-arranged posts 17, rising from the flange 40 of the cam-cylinder. This segmental plate is connected with the pickers, and it is provided with appropriate surfaces, which are so arranged in respect to each other and to the pickers that during the movements of 45 the plate the requisite periodical changes of the pickers are effected, as will presently appear. In the upper edge of the segment, at points adjacent to the respective lifters, are V-shaped recesses 18, while in the lower edge 50 of the segment, adjacent to the respective depressors, are step-like recesses 19, each of the latter being composed of two portions *a* and *b* on different horizontal planes, as shown. Extending outwardly from the sleeves of the 55 picker-arms are studs 20, which intersect the path of the segment, the studs of the lifters, when the latter are in the raised or idle position, resting (against the compression of their springs) upon the upper edge *c* of the 60 segment adjacent to the recesses 18, respectively, and the studs of the depressors, when the latter are in their normally-raised position, extending into the spaces or portions *a* of the recesses 19, respectively.

65 During the knitting of straight-ahead or tubular work the pickers occupy the respective positions just described.

Preparatory to the formation of the heel or the toe of the stocking the operator moves the segment in the direction indicated by the 70 arrow in Fig. 8, a suitable knob or handle 21 being provided for that purpose, thus presenting the recesses 18 to the studs of the lifters, which latter, being unsupported by the segment, are perforce depressed into action by their springs, and at the same time forcing the beveled portions *d* of the segment adjacent to the recesses 19 against the studs of the depressors and forcing the studs down and under the lower portions *b* of said recesses, respectively. Thus the depressors are maintained below their normally active plane. The pickers having been set in the relative positions just described, the cam-cylinder is reciprocated until the desired narrowing of 85 the web has been effected, whereupon the segment is moved to its previous position to release the depressors and raise the lifters out of action. This being done the web is widened correspondingly with the narrowing 90 in the usual way, following which a tubular portion is knit, and so on successively.

The movement of the segment to effect the change from narrowing to widening is attained automatically by means which we shall 95 proceed to describe. To one end of the segment and to the proximate supporting-post 17 is secured a spring 22, the tendency of which is to retract the segment and maintain it in the position first described—*i. e.*, the 100 tubular-knitting position. Fixed to the wall of the cam-cylinder adjacent to this spring is a bracket 23, from which extends a stud 24, carrying a vibratory latch-arm 25, that bears 105 yieldingly upon the upper edge of the segment, a suitably-arranged torsional spring 26 effecting such yielding action. In the upper edge of the segment is a notch 27, which is so disposed in respect to the arm that when the segment is moved by the operator, as and for 110 the purpose stated, the latch engages the notch and thus locks the segment in position against the action of the spring. Hence if the latch be disengaged from the notch the 115 spring will retract the segment to the original position.

To the rearward part of the bed-plate is fixed a bracket 28, provided with bearings in which is supported a rock-shaft 29. On one end of this shaft is a forwardly-extending arm 120 30, on the free end of which rests the rearward arm of a lever 31, that is fulcrumed to a lateral bracket 32 on the bed-plate. The forward arm of the lever rests upon the lower 125 L-shaped arm of a vertical lever 33, that is fulcrumed on a stud projecting from the bracket 32, a torsional spring 35 on said stud acting to maintain the upper arm of the lever 33 normally outward. To the free end of this 130 arm is loosely fitted a stud 36, carrying a head 37, the upper edge of which is preferably oppositely beveled or inclined, a set-screw 38, supported by the boss of the arm, bearing upon the stud and serving to secure

the head adjustably in place. When the arm is in its normal or outward position, the head is beyond the path of the latch-arm; but preparatory to the operation of widening the 5 arm is moved to project the head into the path of said latch-arm, whereupon the latter impinges against the opposed edge of the head and is raised thereby to free the segment.

The described movement of the lever 33 is effected through the rock-shaft 29 and the intermediate connections, the shaft being turned in the direction indicated by the arrow in Fig. 3. The operation of the shaft is automatically attained at the proper time 15 through the medium of a pattern-chain 39, the same being provided with a projection 40, that during the traverse of the chain impinges against an arm 41 on the rock-shaft.

The chain 39 is carried by a sprocket-wheel 20 42, which is loosely mounted on a shaft 43, having bearings supported by the bracket 28. Fixed to or formed on the face of this wheel is a ratchet-wheel 42^a, with the teeth of which 25 engages a pawl 44. This pawl is supported by a vibratory depending arm 45, which is actuated at predetermined intervals—that is, during the knitting of the heel and toe—so as to turn the sprocket-wheel and advance the sprocket-chain intermittently, as will herein- 30 after appear.

On the shaft 7 are the fast and loose pulleys 46 47, respectively, which are periodically connected with a pulley 48 on the main driving-shaft 49 by means of a belt 50. On 35 the outer face of the fast pulley is fixed an eccentric 51, (for a purpose below explained,) adjacent to which, on the shaft 7, is loosely mounted a circumferentially-grooved collar or clutch member 52, carrying an integral 40 sprocket-wheel 53. This wheel is geared by means of a chain 54 with a larger sprocket-wheel 55, the shaft of which is mounted in a suitably-located bracket or hanger 56. Fast 45 on a shaft 57, forwardly of the wheel 55, is a crank-wheel 58, that is connected with the former wheel by means of a pitman 59, said shaft being equipped with a pulley 60, that is belted with and continuously driven from a pulley 61 on the main driving-shaft 49. By 50 this construction a reciprocating rotary motion is imparted to the sprocket-wheel 55 and transmitted therefrom by the belt 54 to the sprocket-wheel 53 on the shaft 7. Hence if 55 the belt 50 be running on the loose pulley and the clutch member be engaged with the fast pulley the shaft 7, and perforce the cam cylinder, will be reciprocated.

During the knitting of tubular work the driving-belt is upon the fast pulley and the 60 clutch member is disengaged from the latter. When the leg or the foot of the stocking, as the case may be, has been completed, the belt is automatically transferred to the loose pulley by mechanism of the following 65 description: Pivoted to a suitably-located lug 62 on the bracket 28, hereinbefore referred to, is the rearward end of a belt-shipper frame

63, through which the belt extends, the outer end of such frame being provided with an appropriate handle. The frame is maintained 70 normally adjacent to the loose pulley by means of a stout spring 64, one end of which is secured to a pin 65 on the shipper-frame and the other end to a pin 66, depending from a bracket or lug 67 on the side of the usual gear-case 68. The shipper-frame is held adjacent to the fast pulley against the action of this spring by means of a suitable latch-arm 69, one end of which is pivotally connected with the frame, as at 70. This arm is bent 80 downward, as at 71, so as to extend under the gear-case, and is provided with a suitably-located notch or recess 72, which engages a lug or projection 73 on said case. A spring 74, interposed between the frame and the arm 85 adjacent to the pivotal connection, serves to maintain the latch-arm yieldingly engaged with the lug or projection. The outer portion of this arm is slotted longitudinally, as at 75, a vertically-reciprocatative pin 76, which 90 is fitted to the lug or bracket 67 on the gear-case, extending through the slot in the arm. On the pin is a collar or shoulder that rests upon the arm, to the end that when the pin is depressed the arm is forced downward and 95 disengaged from the projection, thereby releasing the shipper-frame and permitting the spring to retract it toward the loose pulley and thus to transfer the belt onto the latter.

Rising from the bracket 67 is a post 78, to 100 which is fulcrumed a lever 79, one arm of which is provided with a lateral extension 80, that bears upon the head of the pin 76, while the other arm is provided with a stud 80^a, that projects in proximity to an appropriate 105 pattern-chain 81. On this chain is a projection 81^a, which, at a prescribed period during the traverse of the chain, abuts against said stud, raises the same, and in consequence depresses the pin 76, with the effect above 110 stated.

The chain is carried by a sprocket-wheel 81^x, fast on one end of the shaft 43, above referred to. On the other (or right-hand) end of the shaft are mounted, side by side, two 115 ratchet-wheels 82 83, one of which is fixed and the other loose. These wheels have a corresponding number of similarly-pitched teeth; but the loose wheel is slightly larger than the other, every sixth, say interdental, 120 space of such loose wheel being deepened to register with the corresponding space in the fixed wheel. During tubular knitting the ratchet-wheels are periodically actuated by means of a pawl 84, which is connected with 125 and reciprocated by an eccentric 85 on the driving-shaft 7. The end of the pawl being wide enough to extend over the two wheels it racks the loose wheel a distance of six spaces, in which case, being in a deep space, 130 it engages the fast wheel, moves the same a distance of one tooth, and accordingly moves the shaft. In the next stroke of the pawl it will engage the following tooth of the loose

wheel and rack the latter idly until the succeeding deep space is engaged, whereupon the fast wheel and the shaft will be advanced as before, and so on. As long as the pawl is in action the shaft will be periodically moved. While the shaft is being intermittently rotated the chain 81 is advanced step by step, the number of links, owing to the prolonged intervals between the succeeding movements, 10 being materially reduced.

A suitably - arranged spring 86 tends to maintain the pawl yieldingly in engagement with the ratchet-wheels, while a pair of spring-actuated stop - pawls 87, mounted on the bracket 28, prevents backward movement of the wheels.

When the operation of the machine has been arrested upon the completion of the leg and preparatory to the knitting of the heel, 20 the operator throws into action the diagonal needle-raising cam 8 and effects thereby the inaction of the half-series of needles, as hereinbefore described. He then retracts said cam and subsequently shifts the segmental 25 plate 15 to set the needle-lifters in operative position, as previously explained. This being done the pawl 84 is disengaged from the ratchet-wheels and the clutch member is engaged with the fast pulley to accomplish the 30 requisite reciprocations of the cam-cylinder.

The means for operating the pawl-and-clutch member is of the following construction: Adjacent to the fast pulley is a forwardly-extending hand-lever 88, the rearward 35 end of which is pivoted to a depending boss on an appropriate bracket or extension 89, which may form an integral part of or be secured to the bed-plate of the machine. Extending outwardly from the side of the lever 40 is an arm 90, the outer end of which is bent or inclined upward, as seen. Resting upon this arm is a rearwardly-extending rock-arm 91, the forward end of which is mounted on a stud-shaft 92, supported on a projecting 45 limb of the bracket 89. The forward end of the rock-arm extends freely through a perforated lug 93 on the pawl 84, whereby when the hand-lever is moved laterally toward the fast pulley the inclined portion of the arm 90 50 rides under the rock-arm and raises the latter, which, perforce, lifts the pawl out of action. (See Fig. 5.) A depending stud 94 on the hand - lever enters the circumferential 55 groove in the clutch member 52, so that when the lever is moved as just stated such member, with its connections, is correspondingly moved, a stud 95 on the face of the eccentric thereupon registering with a relatively-located socket 96 in the member and thus locking 60 the reciprocating sprocket-wheel to the fast pulley 46. The hand-lever is normally held in the outer (or tube-knitting) position by the action of a spring 96, which, encircling the shaft 92, bears against a shoulder 96^a on 65 the latter and a lug on the lever. When the lever is moved inward against the stress of the spring, the lever is temporarily locked in

place by means of an appropriate latch, which in this instance comprises a rocking lever 97, fulcrumed to lugs 98 on the hand-lever. The 70 forward arm of the "latch-lever," as it may be termed, is provided with an L-shaped extension that depends freely through a slot in the hand-lever. The horizontal member of the extension projects under the stud-shaft 75 92, being provided with a notch or recess 99, which automatically engages said shaft when the hand-lever is moved inward, such automatic action being effected by means of a spiral spring 100, which bears upon a shoulder 80 on a depending pin 101 on the rear arm of the latch-lever and against the under side of the hand-lever, through which the pin freely extends. It will be seen that by depressing the forward arm of the latch-lever by pressure 85 thereon by hand or by the act of raising the pin (in the manner below described) the latch will be disengaged from the stud and the spring will return the hand-lever and its connections to their original condition. 90

Pivoted to the rearward arm of the latch-lever is the pawl-bearing arm 45, above referred to. This arm is provided with a heel 102, which is so disposed in respect to the eccentric on the fast pulley that when the hand-lever is in the outer position—i. e., during the knitting of tubular work—the heel is out of the path of the eccentric, but that when the hand-lever is moved inward preparatory to the reciprocating operation the heel 102 is projected into the path of the eccentric, so as to be reciprocated thereby. Thus the pawl 44 is actuated to effect the intermittent movement of the sprocket-wheel 42 and chain 39 for the purpose hereinbefore described. The 105 arm is maintained in operative engagement with the eccentric by means of a torsional spring 103, Fig. 1, on the pivotal stud of the arm, there being secured to the rocking lever 97 in advance of the arm a depending stop 110 104, which limits the forward movement of the arm. When the heel of the stocking has been completed, a suitably-arranged projection on the pattern-chain 39 abuts against the pin on the latch-arm, thereby effecting the 115 release of the hand-lever in the manner above described.

The machine being at rest, the operator by novel means hereinafter described returns the half-series of idle needles to action. He then 120 grasps the belt-shipper and transfers the belt onto the fast pulley, whereupon the machine proceeds with the knitting of the foot portion of the stocking in a manner similar to that described in regard to the knitting of the leg 125 portion. Upon the completion of the foot a suitably-arranged stop on the chain 39 coacts with the lever to effect the release of the belt-shipper and the consequent transference of the belt from the fast to the loose pulley, following which the operation of knitting the toe is performed similarly in all respects to that of the heel hereinbefore set forth.

The means above alluded to for returning

the half-series of needles to action when the fashioning operation has been completed is clearly shown in Figs. 8 and 11 of the drawings, as follows: In the wall of the cam-cylinder, at a suitable point beyond the knitting-cams, is formed an inclined slot, to which is edgewise fitted a cam-plate 106 in a manner to be movable into and from the interior of the cam-cylinder. An arm 107, projecting outwardly from this plate, extends freely through a guide-post 108, affixed to the exterior of the cylinder, the outer end of the arm being perforated to receive one end of a suitably-disposed spring 109, which tends to 10 retract the arm and the cam-plate. The path of movement of the plate is eccentric (as distinguished from a radial path) to the axis of the cam-cylinder; but its forward or acting portion is beveled radially in respect to the 15 latter, as at 110, whereby if the cam-plate be pushed (by hand) into the cylinder against the stress of the spring such radial portion during the stroke of the cylinder will engage the first needle-heel in its path and be locked 20 in action thereby, such engaged needle, together with the succeeding upraised needles, thus being directed downward into active position by the cam-plate. Immediately upon the plate escaping the needles such plate, being unrestrained, is retracted by the spring. 25

Instead of the cam-plate being a sliding member it may be a swinging one, as represented in Fig. 12—that is to say, the plate is supported upon one arm of a lever 107^a, that 30 is fulcrumed to a bracket exteriorly of the cam-cylinder, a suitably-disposed torsional spring 109^a tending to maintain the plate in the outward or retracted position. By this construction it will be seen that when the 35 plate is moved into the cam-cylinder the action of the opposed needle-heels thereon prevents the spring retracting the plate until all the needles have been directed down by and below the said plate. Other modifications of 40 this needle-lowering cam will suggest themselves to the mechanic.

As a simple and efficient means whereby the needle-cylinder shall be automatically lowered preparatory to the knitting of the 45 ankle portion of the stocking, to the end that the resultant tightening of the stitches shall reduce such portion, we have provided the following construction, reference being had to Figs. 2 and 3 of the drawings: Depending 50 from the usual needle-cylinder clamp 111 is an arm 112, which is provided at its lower outwardly-extending end with a vertical guide-post 113, that extends freely through the bracket 32 on the bed-plate. Secured to 55 this bracket is the upper end of a depending arm 114, in the lower end of which is formed a circular opening for the reception of an eccentric head 115. The shaft 116 of this head extends into the limbs of a yoke-head 117, to 60 which is affixed the lower end of the arm 112, whereby when the eccentric is turned to the right or to the left the yoke-head and, perforce,

the connected arm and the needle-cylinder are raised or lowered, as desired. Fixed to the shaft of the eccentric is a lever 118, one arm 70 of which constitutes a handle, while the other arm 119 extends in proximity to the pattern-chain 81, before described. At a suitable point on this chain is a lateral projection 80^b, which immediately before the knitting of the 75 ankle is carried by the advancing chain against the lever-arm 119, thereby forcing upward said arm and turning the eccentric in a manner to effect the lowering of the needle-cylinder. This being done the projection 80^c escapes the lever-arm and continues onward with the chain. When it is desired to proceed with the knitting of normal stitches, the operator grasps the handle portion of the lever and returns the eccentric to its original 85 position. A set-screw 120, affixed to a projecting lug on the yoke-head, limits the upward movement of the handle.

To the end that the relative tensions of the 90 stitches during the knitting of the stocking may be nicely predetermined we make the arm 112 vertically adjustable—that is to say, the upper end of the arm is slotted vertically to receive a guide-stud 121 on the bracket 34, and set-screws 122 are fitted to the lower walls 95 of the slot, so as to take against the stud. Hence by properly manipulating these screws the arm and its connected parts may be nicely adjusted vertically and fixed in their positions of adjustment. 100

It will be obvious that by reversing the position of the eccentric in respect to the other coacting parts a loosening instead of a tightening of the stitches will be effected under the circumstances stated. 105

Recurring now to the needle-picking mechanism, it will be observed by reference to Figs. 1 and 13 that there is mounted on the upper end of each of the posts of the depressors an arm 123, from which depends 110 adjacent to the cam 13 and rearward of the picker-arm a plate 124, the forward edge of which is inclined, like the cam. This edge is held yieldingly beyond the cam by the action of a spring 125, one end of which is secured 115 to the arm and the other end to the adjacent supporting-bracket for the cam-head. By this construction when the depressor abuts against a needle preparatory to lowering the latter the retreat of the depressor is temporarily opposed by the plate 124, which latter upon being overcome by the force or thrust of the depressor moves backward to permit the action of the depressor upon its cam. In 120 the absence of this restraining-plate or check-cam we have found that the depressor upon impinging against a needle will recoil, and thus moving slightly downward it will sometimes escape the needle. 125

It will be observed by reference to Fig. 9 130 of the drawings that there is mounted on the usual pivoted thread-guide post 126 a horizontally-disposed end-beveled cam 127, that lies when the post is in active position directly

above the upper edge of the central knitting cam. The function of the cam 127 is to engage the raised or up-thrown needle-heels in its path and thereupon direct them uniformly 5 into line upon the upper edge of the central cam. Thus the proper position of the up-raised needles in respect to the depressing devices will be insured. By swinging outward the pivoted guide-post the cam 127 is 10 withdrawn from the cam-cylinder, so as to permit the removal of needles, &c.

Respecting the sinker or web-holder mechanism herein, 128 represents one of a series of vibratory sinkers which are arranged around 15 the upper end of the needle-cylinder in a manner to alternate with and work between the needles. Each of the sinkers comprises a vertically-arranged lever provided at its lower end with a rounded lug 129, which is fitted to 20 an annular groove 130 in the exterior of the needle-cylinder, and at its upper end with the usual stitch-engaging hook 131. It is also provided at or near its lower end with an outwardly-extending cam-engaging portion 132, 25 the under edge of which is preferably beveled or inclined, as shown. The series of sinkers are retained yieldingly in engagement with the groove 130 and also with the stitches by the action of a coiled spring-band 133, which 30 encircles the sinkers immediately above their cam-engaging members. Encircling the needle-cylinder is a fixed annulus 134, the upper edge of which is grooved radially to receive and guide the lower portions of the several 35 sinkers. Rotatably mounted on this annulus is a ring 135, carrying on its inner wall appropriate cams 136, which are so constructed and arranged that during the rotation of the ring they engage the members 132 of the sinkers 40 successively and effect the requisite disengagement and reengagement of the hooks from and with the stitches during the formation of the latter. The cam-ring is rotated in the usual manner by means of the thread-guide post extending between lugs 137 on the 45 ring. (See Figs. 14, 15, and 16.)

By the construction just described it will be seen that while the sinkers are operated by the cams not only to release but to engage 50 the stitches the sinkers are at other times held yieldingly in action by the spring-band. It will also be seen that should the hook portions of the sinkers when the same are moved inward by the cam engage thick, irregular, 55 or knotty yarn the lower portions of the sinkers, being loosely fitted to the groove in the needle-cylinder, will, by reason of the undue resistance of the yarn to the sinker-hooks, move slightly outward against the action of 60 the spring, and thereby relieve the yarn from the strain to which it would be subjected if the sinkers were merely vibratory from a fixed point, or, in other words, the sinker-hooks when they are thrown inward by the cam act 65 uniformly upon the yarn irrespective of the varying thickness of the latter—that is to say, in the event of the hooks engaging an extra

thick or knotty portion of yarn such hooks will merely pivot on the yarn and the lower portions of the sinkers will move outward 70 against the stress of the spring, but upon engaging a regular portion of the yarn the hooks will be positively moved inward and engaged therewith in the usual manner.

Although a single spring has been shown 75 and described herein as acting upon the sinkers to perform the double function of holding them yieldingly against the stitches and yieldingly against their lower or normal fulcrum to permit the actions just stated, yet it will be 80 understood that independent springs may be employed to effect the double function performed by said spring without departing from this feature of our invention.

The general operation of the machine above 85 described may be summarized as follows: To start, the operator throws the belt-shipper 63 to the right. This runs the belt onto the tight pulley 46 and rotation begins. The lever 88 is held by the spring 96 in right-hand position, 90 the clutch thus being disengaged from pulley 46. Pawl 84 rests upon and works the ratchet 82 on the shaft 43, which shaft carries the pattern-chains 39 and 81. Rotation continues until the lug 80^b on the chain 81 strikes lever 95 arm 119 and, by turning the eccentric 115 and lowering the arm 112 and the needle-cylinder carried thereby, tightens the stitches. The knitting of tight stitches continues until the lug 81^a on chain 81 strikes the stud 80^a on lever 100 79, whereby the pin 76 is depressed, and the latch-arm 69 is thereby also depressed and released from the catch 73, thus permitting the spring 64 to move the shipper 63 to the left and shift the belt to the loose pulley 47. Rotation then ceases and the machine stops. The operator then raises the handle-arm of lever 118 and thereby raises the needle-cylinder to make the stitch length normal. He then 105 pushes the raising-cam 8 into operative position and raises half the needles out of operation by giving the cylinder a partial revolution. He next throws the segment 15 to the left, thereby lowering the lifters 9 into position 110 for action and lowering the depressors 10 out of action. The operator then throws lever 88 to the left and stud 94 thereon moves the clutch 52 to the left into engagement with the fast pulley 46 and starts reciprocation. Pawl 84 is rendered inactive by arm 90 lifting the rock-arm 91 and thereby the pawl 84. Pawl 44 is made active by the shifting of the heel 102 of the arm 45 to a position opposite the eccentric 51. Narrowing commences and continues until a projection 40 on the pattern-chain 39 rocks the shaft 29, which moves the intervening levers 30 31 33 to cause the head 37 to engage the latch-arm 25 and raise it out of the notch 27 in the segment. The segment thus being released, the spring 22 moves it to 120 the right, whereby the lifters are thrown out of action and the depressors thrown into action. Then widening begins and continues until a suitable projection on the chain 39 125

engages the pin 101, thereby rocking the lever 97 and disengaging it from the recess 99. Then the spring 96 moves the lever 88 to the right, in consequence of which the clutch 52 is disengaged from fast pulley 46, reciprocation ceases, and the machine stops. The operator then moves the cam 106 inward into position to engage the needle-heels and gives the needle-cylinder a partial revolution, whereby the said cam throws the inactive needles down into active position. The operator then throws the shipper 63 to the right and the circular knitting is resumed.

It will of course be obvious that our improvements above described may be applied to a machine wherein a rotary needle-cylinder is used in connection with a fixed cam-cylinder, and therefore it is remarked that while we have in certain claims defined the driving-shaft as geared with the cam-cylinder yet we consider that it would be a complete equivalent to gear the shaft with the needle-cylinder. Further, we do not limit our invention to the particular construction and organization herein shown and described, as the same may in many respects be considerably modified without departing from the fair spirit of the invention.

We claim—

30 1. The combination, with a cam-carrier, its knitting-cams, a needle-picker, and means tending to maintain said picker normally in action, of a slide provided with a recessed or cam surface so constructed as to engage the picker and maintain it out of action, when in one position, and, when in another position, to release the picker and permit it to return to action, substantially as described.

2. The combination, with a cam-carrier, its knitting-cams, a needle-picker, and means tending to maintain said picker normally in action, of a slide provided with a recessed or cam surface so constructed as to engage the picker and maintain it out of action, when in one position, and, when in another position, to release the picker and permit it to return to action, substantially as described.

3. The combination, with a cam-carrier, its knitting-cams, a needle-picker, and means tending to maintain said picker normally in action, of a slide provided with a recessed or cam surface so constructed as to engage the picker and maintain it out of action, when in one position, and, when in another position, to release the picker and permit it to return to action, means tending to maintain said slide normally in one position, and means to lock the slide temporarily in the other position, substantially as described.

4. The combination, with a cam-carrier, its knitting-cams, a needle-picker, and means tending to maintain said picker normally in action, of a slide provided with a recessed or cam surface so constructed as to engage the picker and maintain it out of action, when in

one position, and, when in another position, to release the picker and permit it to return to action, means tending to maintain said slide normally in one position, means to lock the slide temporarily in the other position, and means for automatically unlocking the slide, substantially as described.

5. The combination, with a cam-carrier, its knitting-cams, a set of needle-lifters, a set of needle-depressors, and means tending to maintain said lifters and depressors normally in action, of a slide provided with recessed or cam surfaces so constructed that in one position the slide engages the lifters holding them inactive while the depressors are active, and in another position it engages the depressors holding them inactive while the lifters are active, substantially as described.

6. The combination, with a cam-carrier, its knitting-cams, a set of needle-lifters, a set of needle-depressors, and means tending to maintain said lifters and depressors normally in action, of a slide operatively connected with said lifters and depressors and provided in its upper edge at points adjacent to the respective lifters, with V-shaped recesses, and, in its lower edge, adjacent to the respective depressors, with step-like recesses composed each of two portions on different horizontal planes, substantially as described.

7. The combination, with a cam-carrier, its knitting-cams, a set of needle-lifters, a set of needle-depressors, and means tending to maintain said lifters and depressors normally in action, of a device for controlling the idle or active positions of said lifters and depressors at predetermined intervals, a spring to maintain said device in one position, a vibratory latch-arm supported in proximity to said device and adapted to engage it and lock it in another position, and automatic mechanism for disengaging said arm, substantially as described.

8. The combination, with a cam-carrier, its knitting-cams, a set of needle-lifters, a set of needle-depressors, and means tending to maintain said lifters and depressors normally in action, of a device to cause and maintain the active or inactive positions of said lifters or depressors at predetermined intervals, means to maintain said device in one position, a latch-arm supported in proximity to said device and adapted to engage it and lock it in another position, a vibratory lever, a head thereon movable into and out of the path of said latch-arm, a pattern mechanism, and operative connections intermediate said mechanism and lever, substantially as described.

9. In a circular-knitting machine, the combination, with the cam-cylinder, its knitting-cams, and the needle-cylinder, of a shaft geared with said cam-cylinder, continuously-operating mechanism for driving said shaft, means for throwing said mechanism into and out of gear with the shaft, a sprocket-wheel loosely mounted on said shaft, a second shaft,

a sprocket-wheel thereon, a chain connecting said wheels, means for continuously reciprocating the sprocket-wheel on said second shaft, and means for operatively connecting 5 the sprocket-wheel first named with its shaft, substantially as described.

10. In a circular-knitting machine, the combination, with the cam-cylinder, its knitting-cams, and the needle-cylinder, of a shaft 10 geared with said cam-cylinder, continuously-operating mechanism for driving said shaft, a pattern-chain, its supporting and operating parts, means actuated by the chain at predetermined intervals to effect the disengagement of said mechanism from the shaft, a sprocket-wheel loosely mounted on said shaft, means whereby it may be operatively engaged therewith, a second shaft, a sprocket-wheel thereon, a chain connecting the sprocket- 15 wheels, and means for continuously reciprocating the sprocket-wheel on said second shaft, substantially as described.

11. In a circular-knitting machine, the combination, with the cam-cylinder, its knitting-cams, and the needle-cylinder, of a shaft 25 geared with said cam-cylinder, fast and loose pulleys on said shaft, a continuously-driven belt, means for driving the same, means for automatically transferring said belt from the 30 fast to the loose pulley at predetermined intervals, a sprocket-wheel loosely mounted on said shaft, means for engaging it with the fast pulley when the belt is on the loose pulley, a second shaft, a sprocket-wheel thereon, 35 a chain connecting the sprocket-wheels, and means for continuously reciprocating the sprocket-wheel on said second shaft, substantially as described.

12. In a circular-knitting machine, the combination, with the cam-cylinder, its knitting-cams, and the needle-cylinder, of a shaft 40 geared with said cam-cylinder, fast and loose pulleys on said shaft, a continuously-driven belt, means for driving the same, a belt-ship- 45 per frame, a spring tending to maintain the same normally adjacent to the loose pulley, a latch-arm constructed and arranged to maintain said frame adjacent to the fast pulley, a reciprocable pin engaged with the arm and 50 adapted to operate the same, a lever in proximity to said pin, and pattern mechanism adapted to actuate said lever at predetermined intervals, substantially as described.

13. In a circular-knitting machine, the combination, with the cam-cylinder, its knitting-cams, and the needle-cylinder, of a shaft 55 geared with said cam-cylinder, fast and loose pulleys on said shaft, a continuously-driven belt, means for driving the same, a belt-ship- 60 per frame, a spring tending to maintain the same normally adjacent to the loose pulley, a slotted latch-arm pivotally connected with said frame, means engaged by said arm to maintain the frame adjacent to the fast pulley, a vertically-reciprocable pin extending 65 through the slot in, and engaging with, said

arm, and means for depressing the pin, substantially as described.

14. In a circular-knitting machine, the combination, with its driving-shaft, of mechanism for imparting thereto continuous rotary motion, means for maintaining said mechanism normally inactive, devices to maintain 70 said mechanism temporarily in action to effect the continuous rotary movement of said shaft, a second shaft, pattern mechanism thereon, operative connections intermediate the same and said devices, a ratchet-wheel on said second shaft, a pawl to coact with said wheel, means for reciprocating the pawl, 75 mechanism for imparting to the driving-shaft reciprocating rotary motion when the first-named mechanism is inactive, a device for throwing the reciprocating mechanism into action, and means on said device for there- 80 upon moving the pawl out of action, substantially as described.

15. In a circular-knitting machine, the combination, with its driving-shaft, of mechanism for imparting thereto continuous rotary motion, automatic shifting means for rendering 90 said mechanism inactive at certain times, a second shaft, a pattern device thereon, operative connections between said device and the shifting means, a ratchet-wheel on said 95 latter shaft, a pawl to coact with said wheel, means for reciprocating the pawl, mechanism for imparting to the driving-shaft reciprocating rotary motion when the mechanism first named is inactive, a device for throwing the 100 reciprocating mechanism into action, and means on said device for thereupon moving the pawl out of action, substantially as described.

16. In a circular-knitting machine provided 105 with narrowing and widening mechanism, the combination, with the driving-shaft, of mechanism for imparting thereto continuous rotary motion, and means for rendering said mechanism inactive at certain times, mechanism 110 for imparting to the driving-shaft reciprocating rotary motion when the first-named mechanism is inactive, a device for throwing the reciprocating mechanism into action, a second shaft, pattern mechanism thereon for controlling 115 said narrowing and widening mechanism, a ratchet-wheel on said shaft, a pawl to coact with said ratchet-wheel, means for reciprocating said pawl, and means on said device for throwing the pawl into and out of 120 action, substantially as described.

17. In a circular-knitting machine provided with narrowing and widening mechanism, the combination, with the driving-shaft, of mechanism for imparting thereto continuous rotary 125 motion, means for rendering said mechanism inactive at certain times, mechanism for imparting to the driving-shaft reciprocating rotary motion when the first-named mechanism is inactive, a lever for throwing the reciprocating mechanism into action, a second shaft, pattern mechanism thereon for automatically 130

- controlling said narrowing and widening mechanism, a ratchet-wheel on said shaft, a pawl to coact with said wheel, means for reciprocating the pawl, and a latch-arm on said lever adapted to support the pawl and move it out of and into action, substantially as described.
18. In a circular - knitting machine, provided with narrowing and widening mechanism, the combination, with the driving-shaft, of mechanism for imparting thereto continuous rotary motion, means for rendering said mechanism inactive at certain times, mechanism for imparting to the driving-shaft reciprocating rotary motion when the first-named mechanism is inactive, a hand-lever for throwing the reciprocating mechanism into action, a spring tending to maintain said lever in a normal position, a latch-lever mounted on the hand-lever, provisions whereby said latch-lever holds the hand-lever in opposition to the spring, a vibratory arm depending from said latch-lever, a pawl on said arm, means for actuating the arm, a second shaft, a pattern - chain thereon for controlling the said narrowing and widening mechanism, and a ratchet - wheel on said shaft adapted to be operated by the pawl, substantially as described.
19. The combination, with a cam - carrier and its cams, of a diagonally-disposed needle-deflecting cam movable into and from the interior of the carrier, and means tending to maintain said cam normally retracted, the acting edge of said cam being so inclined in respect to its path of movement that when it is moved into the carrier the cam will engage the needle - heels in its path and be locked temporarily in action thereby, substantially as described.
20. The combination, with a cam-cylinder and its cams, of a diagonally-disposed needle-deflecting cam movable into and from the interior of the cylinder in a path eccentric to the axis of said cylinder, the forward or acting edge of the cam being beveled radially in relation to the latter, and a spring tending to maintain said cam normally retracted, substantially as described.
21. The combination, with a cam-cylinder, its cams, a needle-cylinder and its needles, of an eccentric head, means for supporting the same, means operatively connecting said head with the needle-cylinder, a lever connected with said head, one arm of which lever constitutes a handle, a pattern mechanism for actuating the other arm of the lever, and adjustable means for limiting the movement of said lever, substantially as described.
22. The combination, with a cam-cylinder, its cams, a needle-cylinder and its needles, of an eccentric head, means for supporting the same, means operatively connecting said head with the needle-cylinder, and automatic mech-

anism for turning said head, substantially as described.

23. The combination, with a cam-cylinder, its cams, a needle-cylinder and its needles, of an eccentric head, a vertically-adjustable support for said head, means for securing said support in positions of vertical adjustment, and means operatively connecting said head with the needle-cylinder, substantially as described.

24. The combination, with a cam-cylinder, its cams, a needle-cylinder and its needles, of an eccentric head, a support therefor, operative connections between said head and the needle-cylinder, a lever on the shaft of the eccentric, and pattern mechanism for actuating said lever, substantially as described.

25. The combination, with a cam-cylinder, its knitting-cams, and a needle-depressor including a picker-arm, of a plate in rear of the said arm, a support for said plate, and a spring to hold the plate yieldingly toward and adjacent to said arm, substantially as described.

26. The combination, with a cam-cylinder, its knitting-cams, and a needle-depressor embodying a spring-actuated picker-arm and a fixed rearward cam with which it coacts, of a movable plate having its forward edge inclined like the cam and supported adjacent thereto, and means tending to hold said plate yieldingly beyond the cam, substantially as described.

27. The combination, with a cam-carrier, its knitting-cams, the needle-support and its needles, of a series of loosely-mounted vibratory sinkers, arranged to alternate with and work between the needles, each of said sinkers being provided with an inwardly-extending stitch-engaging portion at its upper end, and with an outwardly-extending cam-engaging portion, and normally fulcrumed at its lower inner side, and spring means acting upon the said sinkers to perform the double function of holding them yieldingly against the stitches and yieldingly against their normal fulcrum, whereby during the ordinary operation of the machine the sinkers will rock upon their normal fulcrum when actuated by the cam or by the spring means, but when a sinker engages thick or irregular thread it will be rocked upon the thread as a fulcrum and the lower portion of the sinker will move outwardly by actuation of the cam and the thread will not be cut by the sinker, substantially as described.

In testimony whereof we have hereunto affixed our signatures in the presence of two subscribing witnesses.
